Primary Examiner — Cynthia Ramirez*Assistant Examiner* — Laura H Yu(74) *Attorney, Agent, or Firm* — Harness, Dickey & Pierce, P.L.C.(57) **CLAIM**

The ornamental design for a combined input and output module, as shown and described.

DESCRIPTION

FIG. 1 is a perspective view of the combined input and output module embodying our new design;

FIG. 2 is a top view of the combined input and output module shown in FIG. 1;

FIG. 3 is a front view of the combined input and output module shown in FIG. 1;

FIG. 4 is a rear view of the combined input and output module shown in FIG. 1;

FIG. 5 is a left side view of the combined input and output module shown in FIG. 1;

FIG. 6 is a right side view of the combined input and output module shown in FIG. 1; and,

FIG. 7 is a bottom view of the combined input and output module shown in FIG. 1.

The broken lines in the figures are for the purpose of illustrating portions of the combined input and output module that form no part of the claimed design.
